TILE

Clyde Perdue Cleaver, Lansdale, Pa., assignor to American Encaustic Tiling Company, Lansdale, Pa., a corporation of New York

Filed June 16, 1959, Ser. No. 56,366

Term of patent 14 years

(Cl. D18—2)

I claim:

The ornamental design for a tile, substantially as shown.
